US0D1058420S

(12) **United States Design Patent** (10) **Patent No.:** **US D1,058,420 S**
(45) **Date of Patent:** **** Jan. 21, 2025**

(54) **NECKLACE**

(71) Applicant: **Harry Winston SA**, Plan-les-Ouates (CH)

(72) Inventor: **Tobias Wuest**, New York, NY (US)

(73) Assignee: **Harry Winston SA**, Plan-les-Ouates (CH)

(**) Term: **15 Years**

(21) Appl. No.: **29/891,901**

(22) Filed: **May 11, 2023**

(30) **Foreign Application Priority Data**

Nov. 21, 2022 (WO) WIPO125299

(51) **LOC (15) Cl.** **11-01**

(52) **U.S. Cl.**

USPC **D11/8**

(58) **Field of Classification Search**

USPC D11/6-8, 40-45, 56, 57, 79-81, 85, 86; D3/207, 208, 211
